SWITCH STAND LOCK

Filed Jan. 15, 1929

Inventor

Peter Swanson.

By

Geo. Stevens.
Attorney

UNITED STATES PATENT OFFICE

PETER SWANSON, OF ELY, MINNESOTA

SWITCH-STAND LOCK

Application filed January 15, 1929. Serial No. 332,646.

This invention relates to railroad switches and has special reference to that type of switch stand and lock set forth in my copending application Ser. No. 223,673.

5 The principal object of my present invention is to provide a more simple and efficient type of such lock.

Another object is to provide a lock in which the cooperative part carried by the head of 10 the switch stand is constantly housed therewithin to avoid clogging by snow or ice, and to diminish the liability of tampering.

Other objects and advantages of the invention will appear in the further description 15 thereof.

Referring now to the accompanying drawing, forming part of this application and wherein like reference characters indicate like parts:

20 Figure 1 is a side elevation of a fragmental portion of the upper end of a switch stand and operating lever showing my improved form of lock attached thereto and shown in vertical section;

25 Figure 2 is a top plan view of Figure 1 showing the lock housing in horizontal section;

Figure 3 is a front elevation of the lock with a portion of the handle in section.

30 1 represents a portion of the vertically adjustable head of a common railroad switch stand, it having fixed thereto the extending lug 2, common to such switch stands. However, this lug is disposed somewhat different-

35 ly from the arrangement commonly employed in that it is arched abnormally and designed to be at one end constantly inclosed within the housing 3 of the lock, which is, in this instance, formed integral with the handle 4, the latter being of the common form, and the upper end being bifurcated.

40 At the junction of the bifurcated portion of the handle with the single free extremity thereof is formed a through slot 6 into which the lug 2 always extends, regardless of the position of the handle and this slot opens into the interior of the housing 3, the latter being rectangular in form and oblong vertically. 45 This lug housing or casing comprises the rectangularly shaped member 7 which is of chan-

nel shape in horizontal section and as before stated is formed integral with the handle, the open side thereof being adjacent the lug 2. A division wall 8 is provided in the upper end of the channel-like member 7 and intermediate of it and the wall of said member is pivotally mounted as at 9 the gravity dog 10, the office of which will be described later.

Just beneath the lower edge of the wall 8 is 55 rotatably installed the horizontally disposed supporting portion 11 of the locking bolt which extends through both opposite walls of the member 7 and is provided upon its innermost end with a suitable holding collar 12 attached thereto as by a pin or the like. The locking bolt extends outwardly through the side opposite to that upon which the collar 12 is attached and turned at right angles to reach just beyond the side wall of the housing, and thence bent at right angles parallel with the portion 11 as at 13, thence downwardly as at 14 and again inwardly at substantially right angles as at 15 where it extends through a suitable hole within the lower extremity of the outer portion 16 of the housing, for automatic registration with the hole 17 in the lug 2 when the switch is to be locked, it being obvious that the end 15 of the locking bolt at all times tends to gravitate towards the lug 2, and when not engaged with the hole 17, always slides on the side of the lug this being essential in the proper functioning of the device.

It is to be understood that before the locking bolt is installed the outer casing 16 of the housing is first installed, it being telescopic and fitting down completely over the member 7 and having suitable holes in the opposite walls thereof for registration with like holes in the walls of the member 7 so that in the installation of the device upon a switch lever the housing is completely assembled with the cooperating elements therein before the bolt is placed in position, rendering it impossible to get at any of the mechanism of the lock without first removing the bolt.

As a locking means for the bolt when the latter is engaged with the lug 2, is provided the dog 10 pivoted as at 9 intermediate of the wall 8 and the back of the portion 7 of the

lock casing. This dog has a cutaway portion 19 which surrounds the keyhole 20 through the side thereof with its heavier end 21 tending to at all times gravitate intermediate of the bolt 11 and the side wall of the casing, and for cooperating with such tendency I provide a vertical cutaway portion 22 in the bolt portion 11 so that when the bolt is in locked position the free end of the dog 10 will drop down in between such cutaway portion and the side wall of the housing as shown in the drawings. This dog has an arcuately shaped arm 23 normally functioning on the opposite side and below the keyhole 20 permitting of free insertion of a key in the hole, which when turned upwardly and clockwise as viewed from the drawings (for it cannot be turned otherwise due to the lug 23) will raise the end 21 of the dog 10 and permit the bolt to assume unlocked position, but it will be noted that when the key is thus turned in the lock, and the dog raised, the lug 23 thereof will swing into position opposite the lower end of the keyhole, thus positively preventing the key from being withdrawn from the hole until the dog is permitted to drop and which cannot occur as long as the bolt remains in unlocked position either by the key or otherwise.

Now in the embodiment here illustrated, with the switch lug having an elongated arcuated shaped extension thereupon, once the lock is rocked to unlocked position and the handle 4 raised, the locking end of the bolt having no hole with which to register in the extension of the lug will slide thereupon, and while in this position the key cannot be removed from the lock, but once the handle 4 is lowered so that the locking end of the bolt is engaged within the hole 17 in the lug, then the dog 10 may drop into its position for retaining the bolt in such locked position when the lug 23 will swing away from the keyhole and allow the operator to remove his key.

From the foregoing it is evident that I have devised a marked improvement over the invention described in my former application, my present invention being defined in the following claims, and it will be understood does not include the above described locking means for the bolt and the same is shown, described, and claimed in my former copending application Ser. No. 223,673, above referred to.

Having thus described my invention, what I claim and desire to secure by Letters Patent, is:

1. The combination with a switch stand having a lock engaging lug extending therefrom, and an operating lever, of locking means comprising an open channel shaped member carried by the lever, a housing member for telescopic engagement over the channel shaped member, and a rotatably locking bolt mounted in the members and installable therein after assembly of said members.

2. The combination with a switch stand having a lock engaging lug extending therefrom, and an operating lever, of a lock housing carried by the lever, the lug constantly extending therewithin.

3. The combination with a switch stand having a lock engaging lug extending therefrom, an operating lever, and a rotatable locking bolt, of a lock housing carried by the lever, for housing the lug and in constant engagement therewith, said housing being of two cooperative parts, and means whereby the locking bolt when assembled within the housing locks same.

4. The combination with a switch stand having a lock engaging lug extending therefrom and having a hole therein, and an operating lever, of a lock housing carried by the lever, and a rotatable locking bolt mounted within the housing and in constant engagement with the lug.

In testimony whereof I affix my signature.

PETER SWANSON.
